(57) **CLAIM**

The ornamental design for a front seat, as shown and
described.

DESCRIPTION

FIG. 1 is a left front perspective view of a font seat showing
our new design;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a top plan view thereof.

The broken lines illustrate environmental structure only and
form no part of the claimed design.
